THOMAS ALLSOP AND HARRY H. WIGGLESWORTH, OF PHILADELPHIA, PENNSYLVANIA, ASSIGNORS TO THE PHILADELPHIA DRYING MACHINERY COMPANY, OF PHILADELPHIA, PENNSYLVANIA, A CORPORATION OF PENNSYLVANIA.

DRYING MACHINE.

Application filed May 28, 1924. Serial No. 716,328.

This invention relates to drying machines for hosiery and the like, and it has more particular reference to that type of machine in which rows of forms are progressed 5 through a drying enclosure and exposed relative thereto for stripping and reclothing.

An object of this invention is to provide an exceptionally compact machine of the typified character which is automatic in action and efficient in operation.

Other objects have reference to a novel arrangement of repressing rollers functional to remove any creases remaining in the articles dried as they leave the drying enclosure 15 for "stripping;" and an automatically actuated closure at the "boarding" station whereby undue escape of the drying medium is prevented.

With the foregoing and other objects in view, as will be apparent from the following description, this invention consists in certain novel features of construction, combinations and arrangements of parts hereinafter fully set forth, and more specifically defined by 25 the subjoined claims.

In the further disclosure of the invention reference is made to the accompanying sheets of drawings, constituting a part of this specification, and in which corresponding parts are distinguished by the same indices throughout the several views.

Fig. I, is a horizontal section of a hosiery drying machine conventionally embodying this invention, and taken approximately on the plane indicated by the arrows I—I in Fig. II.

Fig. II, is a front elevation of the machine.

Fig. III, is a vertical section taken substantially on the line III—III in Fig. II.

Fig. IV, is a vertical section taken approximately on the plane indicated by the arrows IV—IV in Fig. I; and,

Fig. V, is a fragmentary detail of a closure hereinafter more fully explained.

In the particular embodiment of the invention chosen for illustrating its characteristics and mode of operation, it will be observed the same comprises an enclosure comprehensively designated by the numeral 6, and having removable thermo-insulated panels 7, 8, 9. This enclosure 6 is subdivided

by a partition 10 to provide a drying chamber 11 and a compartment 12 conventionally housing a nest of radiator coils 13, to which 55 heating medium is supplied—by a connection 14—and circulated in accordance with well known practice. The partition 10 is fitted with a housing 15 for a vertically rotatable fan 16, the shaft 17 whereof, is journaled in bearings 18, and adapted to be driven by a belt drive 19, from any convenient source of power; and said partition is also provided at its upper part with an opening 20 through which the drying medium circulates as indicated by the arrows 60 on Fig. II. In order to ensure even distribution of the drying medium throughout the chamber 11, we employ a transverse slatting 21, of appropriate material, that is 65 closely juxtaposed above the highest elevation of the hosiery forms 22, as will be clearly appreciated by an examination of Fig. IV, more particularly. In addition to the slatting 21, a vertical apron 23 is fitted 70 at the rear of the machine in spaced relation to the egress opening 24, to prevent undue escape of the drying medium and moist atmosphere therat.

The hosiery forms 22 which are attached 75 by clamps 25 to carrier rails 26, in accordance with known practice in the art, it is to be particularly remarked, are in accordance with this invention fitted with small anti-friction rollers 27 which are adapted to 85 traverse co-planar tracks 28, of appropriate cross-section provided for the purpose near the bottom of the drying chamber 11.

In addition thereto we provide, at both 90 ends of each carrier rail 26, a laterally directed stud or pin 29, respectively afforded guidance in a substantially rectangular raceway or slot 30, in the aforesaid partition 10, and an inner end wall 31—Fig. I—in closely spaced relation to the removable panel 7.

Associated with the raceways or slots 30 are endless conveyor chains 32, trained about idler sprockets 33, and intermittently rotated chain wheels 34 fixed upon a transverse shaft 35, journaled in the machine sub-framework. This shaft 35 is rotated by an intermittent bevel couple 36, in turn driven by a worm-reduction 37, and a belt drive 38, from any convenient source of power.

Elevation and spaced progression of successive carrier rails 26 up and down the vertical, as well as along the top, portions of the raceway or slot 30 is accomplished 5 through the medium of laterally lugged links 39 placed at intervals in the conveyor chains 32, in the manner hereinafter fully explained; and, as will be readily appreciated by those conversant with the art to 10 which this invention appertains. However, it is to be remarked that the lugged links 39 project laterally at each side of the conveyor chains 32. On the other hand, progression of the successive carrier rails 26, in 15 abutting relation, over the co-planar tracks 28—a distance conforming with the width of said carrier rails—is effected by means of hooked draw rods 40 supported in guides 41, and coupled by connecting-rods 42, to 20 rock arms 43, fulcrumed at 44, and adapted for oscillation by the outer portions of the lug-links 39 in opposition to contractile springs 45.

Referring again to the drying chamber 25 11, the same is provided with a semi-curved roof 46, and an automatically opened flexible door 47 that affords entry for each successive carrier rail 26 of clothed forms 22. This door 47, as best shown by Fig. V, is 30 fabricated from articulated sheet material strips 48, with the ends afforded guidance in channel section runners 49. The mechanism effective to raise the door 47, comprises opposed lever-arms 50, fulcrumed at 35 51, and having their free ends 52 disposed in the path of successively descending lug links 39 aforesaid. These lever-arms 50, are operatively connected by rods or links 53 to compound leverages 54, 55 fulcrumed at 56, 40 and in turn hinged connected to the flexible door 47 by lugs 57.

Associated with the egress opening 24, and aligning over the successively advanced row of forms 22—ready for ejection from the 45 machine for stripping—are a pair of repressing rollers 58, freely journaled between bearing levers 59, fulcrumed at 60, and normally maintained in close contact under the action of contractile springs 61, said levers 50 59 having relatively curved free ends 62 for a purpose hereafter explained. 63 are laterally projecting flanges affording guidance for the carrier rails 26 during transference over the top of, and down the front of, the 55 drying chamber 11.

Having detailed the various structural features embodied in our novel drying machine, and their respective coordination, it 60 will be readily apparent that when rotary motion is imparted to the worm-reduction 37, the endless conveyor chains 32 will be intermittently progressed through the medium of the bevel couple 36. Now, let it be assumed that said chains 32 are directionally progressed—as indicated by the arrows

thereon in Figs. III and IV—and that an operative is stationed at the front of the machine to clothe the forms 22, with another at the rear thereof to strip said forms, the succession of operative movements may be 70 briefly summarized as follows:—When the temporarily halted carrier rail 26 at the front of the machine has had the row of forms 22 thereon clothed with wet hosiery, it will be readily seen that the next progressive movement of the endless conveyor chains 32 will advance the lugged links 39 onto the free ends 52 of the lever arms 50, and move the same, together with transfer of said rail downwardly along the inwardly inclined portions of the raceways or slots 30 from the full-line position shown in Fig. III, to that indicated by dotted-lines in Fig. IV, and place the moved carrier rail 26 on the co-planar tracks 28. At this juncture, it is to 80 be particularly noted that downward oscillation of the lever-arms 50 actuates the compound leverages 54, 55 and elevates or opens the flexible door 47, through the instrumentalities hereinbefore set forth. Coincident with the arrival of the carrier rail 26 at the bottom of the inwardly inclined portions of the slots 30 on to the tracks 28, the studs 29 will be disengaged from the free ends 52 of the lever arms 50—as clearly 90 indicated in Fig. IV—and at the same moment the outwardly projecting portions of simultaneously progressed lug links 39 contact with the rocker arms 43, and through the rods 42 and hook-ended draw-rods 40, advance the just referred to series of forms 22 into the drying chamber 11, concurrently with the movement of a rail 26 into position for elevation and stripping. Incidentally, it is noteworthy that the flexible door 47 is 100 designed and proportioned to gravitate back to closed position, whereas the draw-rods 40 are retracted by the contractile springs 45, as will be clearly understood without further explanation. 105

The next progressive movement of the endless conveyor chains 32, will, through the medium of the lug links 39 previously disengaged from the rocker arms 43, engage below the studs 29 of the carrier rail 26 at the 115 extreme back of the enclosure 6, and elevate the same to the position indicated at the upper right hand corner of Fig. IV, and concurrently therewith the previously elevated carrier rail 26 will be transferred to the position shown by the dot-and-dash lines at the left hand of said figure. During the elevation of the carrier rail 26 just referred to it will be apparent that forms 22 thereon will pass between the re-press rollers 58, 58 in opposition to the contractile springs 61, whereby the dried hosiery thereon will receive a finishing roll, serving to smooth out and eliminate any chance creases or the like not removed by the drying action during progress 125 130

through the chamber 11. As the carrier rail 26 emerges above the re-press rolls 58, 58, the studs 29 thereon are engaged by the relatively larger curved free end 62 of the outer bearing lever 59, with the result that the forms 22 thereon are automatically thrown into the dotted-line-downwardly inclined-position for stripping by the outer rollers 27 riding over and tripping free of the sharper curved free ends 62, of the inner bearing levers 59 under the retractile action of the springs 61, as will be readily understood by an examination of Fig. IV more particularly. It will, of course, be appreciated that the progressive movements of the endless chain conveyors 32, are co-ordinated to ensure positive positoning of the carrier rails 26 to effect the operations above set forth.

After the forms 22 have been stripped 20 the following progressive movement of the endless chain conveyors 32, will advance the carrier rail 26 over the top of the chamber 11, and downwardly with respect to the front thereof, into the position shown best 25 in Figs. II and III, where said forms are reclothed with fresh wet articles to be dried, the laterally projecting flanges 63, 63 hereinbefore referred to serving to guide the carrier rails 26 with precision as will be 30 readily apparent without further description or explanation.

From the foregoing it is thought that the successive progressive motions aggrouped in our novel drying machine will be fully 35 understood, while the inherent advantages pertaining thereto are so obvious as not to necessitate specific enumeration. Furthermore it is to be clearly understood that we hereby reserve the right to make such necessary changes in the form, proportions, and 40 minor details of construction as may be properly encompassed by the scope of the subjoined claims. For example, the repressing rollers 58, 58, may be disconnected 45 whereupon the machine will continue to function as a dryer with equal efficiency; but we do desire, in conclusion, to particularly emphasize the compact character of our 50 machine, whereby greatly increased economy in production, maintenance, and operation result.

Having thus described our invention, we claim:

1. A drying machine comprising an enclosure, a series of form carriers, means for boosting the carriers through the enclosure in close relationship, means whereby consecutive carriers are vertically elevated to exposedly eject and downwardly-incline the forms for stripping, subsequently upwardly-swung and progressed to reclothing location, and thereafter vertically lowered and advanced into and through the drying enclosure; and means cooperative with the aforesaid carriers to effect the downward

and upward inclination of the forms while exterior of the drying enclosure.

2. A drying machine comprising an enclosure, a series of form carriers, means for boosting the carriers through the enclosure 70 in close relationship, means whereby consecutive carriers are elevated to outwardly expose the forms for stripping, subsequently progressed to reclothing location, and thereafter lowered and advanced into the 75 drying enclosure; means cooperative with the aforesaid carriers to decline the forms during ejection from the drying enclosure; and a flexible door for the enclosure adapted to be automatically opened to permit entry 80 of the re-clothed forms.

3. A drying machine comprising an enclosure, a series of form carrying rails, means for boosting the rails through the enclosure in close relationship, and co-operative 85 means whereby consecutive rails are elevated and rocked to exteriorly eject and decline the forms for stripping, subsequently progressed to reclothing location, and thereafter lowered and boosted into the drying 90 enclosure.

4. A drying machine comprising an enclosure, a series of rails carrying aligned forms, means for boosting said rails through the enclosure in close relationship, co-planar 95 tracks along which the rails are progressed, endless conveyors whereby consecutive carriers are elevated to eject the forms for stripping, subsequently progressed to reclothing location, and thereafter lowered and advanced into the drying enclosure, and means functional to swing each form carrier downward concurrent with its arrival at ejected location.

5. A drying machine comprising an enclosure, a series of form carriers, substantially rectangular raceways over which the form carriers are progressed, means whereby said forms are boosted while in the drying enclosure, consecutively elevated and exteriorly declined for stripping, subsequently progressed into vertical disposition for reclothing, and thereafter lowered for boosting into the drying enclosure.

6. In a drying machine including an enclosure and a series of form carriers for intermittent progression therethrough, spring influenced members cooperative with said form carriers to automatically decline the forms for stripping.

7. In a drying machine including an enclosure and a series of form carriers for intermittent progression therethrough, spring influenced levers having curved ends functional to rock the form carriers and decline the forms for stripping.

8. In a drying machine including an enclosure and a series of form carriers for intermittent progression therethrough, spring influenced levers supporting freely rotatable

rollers through which the forms and carriers pass, said levers having relatively curved free ends adapted to rock the form carriers and exteriorly decline the forms into position for strippage.

9. In a drying machine including an enclosure and a series of form carriers for progression therethrough, the combination of a gravity-fall flexible door for said enclosure, compound leverages hingedly connected to said door, and fulcrumed lever

arms adapted to rock said compound leverages with the free ends thereof projected into the path of successively entering form carriers whereby the door is automatically elevated coincident with the descent of a carrier to enclosure-entering position.

In testimony whereof, we have hereunto signed our names at Philadelphia, Pennsylvania, this 23rd day of May, 1924.

THOMAS ALLSOP.

HARRY H. WIGGLESWORTH.
